HYDRAULIC GOVERNING APPARATUS

Anthony F. Schwendner, Essington, Pa., assignor
to Westinghouse Electric & Manufacturing
Company, East Pittsburgh, Pa., a corporation
of Pennsylvania

Application March 2, 1938, Serial No. 193,487

22 Claims. (Cl. 264—14)

My invention relates to hydraulic governing apparatus for rotating machinery, such as prime movers, and it has for an object to provide apparatus of this character which is versatile from the point of view of meeting different operating requirements.

A further object of my invention is to provide a pressure transformer governor with an impedance device capable of being arranged to secure standard or ordinary governing operation, sluggish or base load operation, and anticipating operation where sudden load changes are encountered.

A further object of my invention is to provide a governor providing for isochronous operation or a desired degree of speed correction adjustment.

A further object of my invention is to provide a transformer governor having impedance means with connections to secure standard, base load, anticipating and isochronous operations of the governor.

A further object of my invention is to provide a governing mechanism including a pressure transformer, which utilizes a primary pressure to secure a secondary or regulating pressure bearing predetermined relation to the primary pressure, together with a servo-motor for actuating the admission valve of a prime mover and including a pilot valve actuated by means of a relay, which, in turn, is operated by means including fluid under secondary pressure coming from the transformer.

In the patent to Zelov, No. 1,966,841, July 17, 1934, there is disclosed and claimed a pressure transformer and in my patent, 2,009,417, July 30, 1935, there is disclosed and claimed two types of transformer governors utilizing the principle of the Zelov patent, one type providing for anticipatory operation, where sudden load changes are encountered, and the other type providing for sluggish or base load operation in order that frequency fluctuations may be suppressed and the application thereof to the governor prevented. In accordance with the present invention, I provide a single transformer governor which may be readily adjusted, not only for anticipatory and base load operations, but also for standard and speed-correcting operations as well.

These and other objects are effected by my invention as will be apparent from the following description and claims taken in accordance with the accompanying drawings, forming a part of this application, in which:

Fig. 1 is a side elevational view showing a prime

mover with my improved governor mechanism applied thereto;

Fig. 2 is a fragmentary vertical sectional view showing the transformer governor and taken along the line II—II of Fig. 3;

Fig. 3 is a vertical sectional view taken along the line III—III of Fig. 2 and showing, in addition to the transformer governor, the servomotor apparatus;

Fig. 4 is a sectional view taken along the line IV—IV of Fig. 2;

Fig. 5 is a sectional view taken along the line V—V of Fig. 2; and

Fig. 6 is a diagrammatic view showing the passage connections for the pilot valve of the transformer governor.

Referring now to the drawings more in detail, in Fig. 1, there is shown transformer governor apparatus, at 6, controlling the admission valve 7 of a prime mover, for example, the turbine, at 8, including a cylinder 9 and a rotor 10.

The rotor 10 drives the impeller 13 (Fig. 3) to provide a source of fluid under pressure for reversed flow impeller apparatus, such as disclosed and claimed in the patent to Bryant, No. 2,035,689, March 31, 1936, the reversed flow impeller apparatus including an orifice 14 through which fluid under pressure is supplied from the impeller 13 to the pressure passage 15 in which the magnitude of pressure depends upon the effect of the inclined passage 16 formed in the rotor, the passage 16 providing for the escape of fluid against the centrifugal head of such passage, and, therefore, providing for maintenance of fluid under pressure in the pressure passage 15 varying substantially as the square of the speed of the rotor, irrespective of fluctuations in the delivery pressure of the impeller 13, it only being required that the delivery pressure of the latter shall be sufficiently high and any excess of fluid escaping through the inclined passage 16. Fluid under pressure in the passage 15 is supplied to the transformer governor, at 17, which provides a secondary or regulating pressure for actuation of the servo-motor, at 18, the latter being connected to the lever 19 of the admission valve 7.

The apparatus, at 6, preferably includes a multiple part body 20 having passages, chambers, and cylinders formed therein, as hereinafter described, and provided with a cover 21 through which the actuating rod of the servo-motor extends for connection to the valve lever 19 as shown in Figs. 1 and 3.

Referring to the transformer governor, at 17, the stationary or body structure thereof is pro-

vided with a chamber 22 connected to the pressure passage 15 and having its upper end closed by the bellows 23, the upper end of the latter being connected to the cover plate 24 and the lower end 5 being connected to an abutment plate 25. A spring 26 has its upper end connected to the abutment plate and has its lower end connected to the adjustable plug 27 carried by the threaded stem 28. By turning the stem in any suitable 10 manner, the plug 27 may be positioned to secure a desired spring force or tension. The stem 28 also has an abutment 29 engaged by the bell crank 30 fulcrumed at 30a and which may be moved angularly about the latter by means of the push 15 rod 31 actuated either by means of the hand wheel 32 or the speed changer motor 33. Thus, by changing the spring force or tension by any of the means referred to, the governor may be adjusted.

20 The abutment 25 forming a closure for the upper end of the pressure chamber 22 has thrust bearing engagement, at 35, with respect to the lower end of the piston 36 arranged in the cylinder 36a formed in the body structure, the piston 25 being turned in any suitable manner, as by a turbine wheel 37, to avoid the effects of static friction.

The spinner piston 36 is provided with upper and lower piston portions 38 and 39. In neutral, or cut-off position, the upper piston portion just laps the pressure port 40 and the lower piston portion 39 just laps the exhaust port or connection 41. The piston is reduced between the piston portions 38 and 39, the reduction cooperating with the cylinder 36a to provide a secondary or regulating pressure chamber or source 42. The pressure port 40 is supplied from any suitable source of fluid under pressure, for example, by the passage 40a from the impeller 13 40 and the exhaust port 41 is connected to the drainage apparatus. Fluid under secondary or regulating pressure is supplied from the chamber 42 by the supply passage or conduit 44 to the servo-motor apparatus, at 18. The body 20 45 is also provided with a passage 45 for connection to bleeder control mechanism where the governor is supplied for a turbine of that type.

From the apparatus so far described, it will be apparent that, if there is a change in primary 50 pressure in the passage 15 incident to load change, the relationship of the force of such pressure and of the spring 26 acting on the abutment 25 changes and the spinner piston is actuated to bring about change in secondary or regulating pressure and actuation of the servo-motor apparatus, at 18.

Referring now to the servo-motor apparatus, at 18, in Fig. 3, there is shown a pressure chamber 47 defined in part by upper and lower bellows 60 elements 48 and 48a connected to an abutment plate 49, the upper bellows being of smaller diameter than the lower bellows and the abutment plate, therefore, providing a pressure abutment face forming a part of the enclosure of the pressure chamber 47 and providing for expandable and contractible operation of the latter with upward and downward movement of the abutment plate 49. A cup valve 50 is connected to the abutment plate 49 and it extends into the 65 pressure chamber 51 supplied with fluid under pressure by an orifice 52 from the chamber 52a communicating with the discharge of the impeller 13.

The lower end of the cup valve 50 is normally 70 closely disposed with respect to the upper end

of the pilot valve 53 in the cylinder 54, the pilot valve having upper and lower piston portions 55 and 56 normally covering pressure ports 57 and 58 and an intermediate piston portion 59 normally covering the exhaust port 60.

The operating cylinder 61 has upper and lower admission and exhaust passages 62 and 63 connected to the ports 64 and 65 formed in the cylinder 54. An operating piston 66 fits the cylinder 61 and it is connected to a rod 67 whose upper 10 end is pivotally connected to the lever 19. The rod 67 is also connected to a lever 68 fulcrumed, at 69, and having an abutment 70 which engages underneath the abutment 71, adjustably connected, as by screw threads, to the stem 71a attached to the upper end of the spring 72, the lower end of the latter being connected to the ring 73 whose upper surface is engaged by the abutment member 74 connected to the rod 75 having a conical head 76 at its lower end which 20 engages the seat 77 formed interiorly of the cup valve 50.

A spring 79 bears against the lower end of the pilot valve 53, the latter being positioned due to the opposed forces of such spring and of 25 the fluid pressure in the chamber 51.

Normally, the pilot valve 53 occupies a neutral, or cut-off, position, the tendency of pressure of fluid to build up in the chamber 51 acting on the upper end of the pilot valve against the 30 force of the spring 79 to provide for escape of fluid through the bore 53a, to the drain. Accordingly, the position of the pilot valve 53 is determined by the cup valve 50, the position of the cup valve and the construction of the pilot 35 valve, providing for forces acting on the latter to cause it to follow the cup valve, constituting a relay arrangement.

If there is a change in secondary or regulating pressure supplied to the pressure chamber 47, the cup valve 50 moves with the result that the pilot valve 53 is caused to move; however, the force of the secondary or regulating pressure is not used directly to effect such movement but actuates said relay serving this purpose.

If the cup valve moves down, then the effect of such movement is to restrict the escape of fluid from the chamber 51 with the result that pressure building up in the latter causes the pilot valve to move downwardly. On the other hand, if the cup valve rises, then the resistance to escape of flow from the chamber 51 decreases, lowering the pressure in the latter chamber and diminishing the force of such pressure acting on the upper end of the pilot valve 53, and the preponderating force of the spring 79 causes the pilot valve 53 to move upwardly.

Hence, the abutment 49, the cup valve 50, the pressure chamber 51, the upper end of the pilot valve 53, the orifice 52, and the valve relation 60 existing between the cup valve and the upper end of the pilot valve provide a relay utilizing small changes in secondary or regulating pressure force to control the application of pressures to the pilot valve 53 such that the latter is moved 65 as determined by the positioning of the cup valve 50 in consequence of change in secondary or regulating pressure.

Just as soon as the pilot valve 53 moves from neutral position, then the ports 64 and 65 are 70 brought into relation to supply motive fluid to one end of the operating cylinder 61 and to exhaust from the other end thereof, thereby bringing about movement of the operating piston 66, accompanied by movement of the lever 68 and 75

consequent change in the force of the spring 72, the arrangement being such that, when the cup valve 50 is moved in consequence of change in secondary or regulating pressure, the operating 5 piston will move until the force of the spring 72 is changed sufficiently so that the latter force and the force of the secondary or regulating pressure acting on the cup valve will be in equilibrium with the cup valve in position for neutral 10 position of the pilot valve 53.

While the cup valve 50 for the servo-motor apparatus has been described as having its position determined by forces of the spring 72 and of the secondary or regulating pressure, it will 15 be apparent that, if desired, other forces may be applied thereto. For example, there is shown a passage 81 extending within the lower bellows 48a and which may be used for supplying bleeder pressure to the interior of the bellows where the 20 governing mechanism is applied to a bleeder turbine.

Referring now to the features of the transformer governor providing for different types of operation, namely, standard or ordinary operation, 25 anticipating operation, sluggish or base load operation, or isochronous operation, the upper piston portion 38 of the piston valve 36 has an upper abutment face 83 closing the upper pressure chamber 85 and the lower piston portion 39 has a lower pressure abutment face 84 closing the pressure chamber 86. A first passage 87 connects the source of secondary pressure 42 with the upper pressure chamber 85 and it includes a needle valve 88. An accumulator 89 is connected 30 by a second passage 90 to the upper pressure chamber 85 and it includes a valve 91. A third passage 92 is joined to the second passage 90 between its valve and the accumulator and is connected to the supply passage 44, the third passage 40 sage having a valve 93 therein. A fourth passage 94 connects the secondary or regulating pressure space or source 42 with the supply passage 44 and it includes an adjustable needle valve 95.

45 With this arrangement of passages and valves, it will be apparent that the impedance effect of the accumulator 89 may be avoided altogether, as is the case for standard or ordinary operation; it may be exerted on the upper pressure chamber 50 85 when anticipating governing is desired; or it may be exerted on the supply passage 44 for sluggish or base load governing.

For standard operation, the valves 88 and 95 would be in full open position and the valves 91 55 and 93 would be closed, this being the relation to secure application of secondary pressure to the upper abutment face 83 without lag or impedance. If there is a change in primary pressure, the secondary pressure changes in consequence thereof, the abutment or piston areas 25 and 83 maintaining the pressures in fixed ratio for the reason that the force of primary pressure on the area 25 is balanced by that of secondary or regulating pressure on the area 83. By 60 suitable choice of areas, a change in primary pressure may be accompanied by any desired magnified change in secondary or regulating pressure.

For anticipating operation, which is desirable 70 where large changes in load are encountered, the valve 88 is adjusted to provide a restriction between the secondary pressure source 42 and the upper pressure chamber 85, the valve 91 is opened so that communication is established between the accumulator 89 and the upper chamber 75

ber 85, the valve 93 is closed to interrupt the second passage 92 and the valve 95 is opened. This adjustment of the valves subjects the upper chamber 85 to the impedance effect of the ac- 5 cumulator.

In order that the impedance effect of the ac- 10 cumulator may be exerted on the supply passage 44, incident to sluggish or base load operation, further changes in the connections are effected, the valve 88 being opened, the valve 95 being ad- 15 justed, the valve 93 being opened, and the valve 91 being closed, whereby restricted communica- 20 tion is established between the secondary source or chamber 42 and the supply passage 44 by means of the needle valve 95 and the accumulator 15 is brought into communication with the supply passage by means of the second passage 92.

The governor is also provided with a fifth pas- 25 sage 96 connecting the upper pressure chamber 85 and the lower pressure chamber 86, the pas- 30 sage containing an adjustable needle valve 97 and a cut-off valve 98. A second accumulator 99 is connected to the passage 96 between the needle valve 97 and the lower chamber 86. To adjust the governor for isochronous operation, the valve 98 is opened and the valve 97 is adjusted so as to provide for the application of the impedance effect of the accumulator 99 on the lower pres- 35 sure chamber 86, whereby a desired lag in the relation of the pressures in the upper and lower chambers 85 and 86 may be secured. In addition to opening the valve 98 and adjusting the valve 97, the valve 88 would be opened fully so that secondary or regulating pressure is supplied to the upper pressure chamber 85 without lag or restriction, the valves 91 and 93 would be closed to isolate the first accumulator 89 both from the upper chamber 85 and from the supply passage 44, and the valve 95 would be fully opened.

The operation of the apparatus described is as 40 follows: The turbine or prime mover provides, by means of the impeller 13, a source of fluid under pressure, which source is used both for motive fluid purposes and for the purpose of deriving the primary controlling or governing pressure, as 45 well as a source of pressure for lubrication where the fluid is lubricant, the primary pressure being supplied by the passage 15 to the pressure chamber 22 whose upper end is closed by means of the movable abutment 25. The force of the primary 50 pressure tending to move the abutment upwardly is resisted by means of the spring 26. The abutment 25 abuts the lower end of the spinner piston valve 36 by means of the thrust bearing 35, the spinner piston valve being turned by a 55 turbine element 37 in order to avoid the effects of static friction. The spinner piston valve co- operates with the valve cylinder to provide a secondary or regulating pressure source 42 which is placed in communication either with the pres- 60 sure port 40 or with the exhaust connection 41 in order to bring about change in secondary or regulating pressure.

Other means must be employed in connection 65 with the pilot valve if the secondary or regulating pressure is to be changed as determined by the change in primary pressure. Accordingly, the first passage 87 provides for the supplying of fluid under secondary or regulating pressure from the source or chamber 42 to the upper pres- 70 sure chamber 85 under all conditions of operation, the passage providing for the application of pressure to the upper piston face 83 in opposition to the primary pressure, that is, if there is an increase in primary pressure, causing upward 75

movement of the abutment 25 and consequent upward movement of the spinner piston, the secondary or regulating pressure increases due to the pressure port being placed in communication with the secondary pressure source 42, but, with increase in secondary or regulating pressure, the force applied to the upper piston face 83 increases with the result that equilibrium of the spinner piston is restored with the latter in neutral position.

If the valve 88 is adjusted and the accumulator 89 is connected to the upper pressure chamber 85, the secondary source or chamber 42 being in open communication by means of the passage 94 with the supply passage 44, then change in pressure in the upper chamber 85 will lag with respect to changes occurring in the chamber 42 with the result that sufficient over-travel operation of the spinner piston will occur to secure 20 anticipating operation.

For standard operation, the accumulator 89 is isolated both from the upper pressure chamber 85 and from the supply passage 44 by closure of the valves 91 and 93, the secondary chamber or 25 source 42 being in full communication with the upper pressure chamber 85 by means of the open passage 87 and with the supply passage 44 by means of the open passage 94.

Where base load governing is desired and the 30 imposition of frequency fluctuations on the governor are to be avoided, then full communication of the secondary pressure source or chamber 42 with the upper chamber 85 is established by means of the passage 87, the valve 88 being 35 fully open, the accumulator 89 is isolated from the upper pressure chamber 85 by closure of the valve 91, communication of the secondary pressure source or supply 42 by means of the passage 94 with the supply passage 44 is restricted by 40 adjustment of the needle valve 95, and the impedance effect of the accumulator 89 is exerted on the supply passage 44 by opening the valve 93. For isochronous operation, the apparatus is arranged as hereinbefore described for standard 45 operation, that is, with a change in load, the secondary or regulating pressure supplied by the governor changes to change the steam admission suitably to the new load; however, with this arrangement, some change in speed is inherently 50 necessary. Therefore, in addition to features providing for the standard arrangement, the governor includes additional features for correction of the secondary or regulating pressure so that the speed may be wholly or partly corrected or 55 compensated at different loads.

More particularly, for isochronous operation of the apparatus, the valve 88 is opened so that fluid under secondary pressure is supplied through the passage 87 to the upper pressure 60 chamber 85, the accumulator 89 is isolated both from the chamber 85 and the supply passage 44 by closure of the valves 91 and 93, the valve 95 is opened to establish full communication by means of the passage 94 between the secondary 65 pressure source or chamber 42 and the supply passage 44, and the valve 98 is opened and the valve 97 is adjusted so as to provide for restricted communication between the upper and lower chambers, the accumulator 89 exerting its 70 effect on the lower chamber.

Preferably the valve 88 is arranged, not only to open and close the passage 98 as already described, but also to control communication of the lower chamber 86 with a drainage passage 75 100. To this end, in Fig. 5, the valve 88 is shown

as being of the reciprocating piston type and has piston valve portions 101 and 102, the piston valve portion 101 being arranged to open and close the passage 98 and the piston valve portion 102 being arranged to close the drain passage 100. With the piston valve portion 101 in the position closing the passage 98, the passage 103 formed in the piston valve affords communication of the lower chamber 86 with the drain passage 100; and, with the piston valve portion 101 moved so as to fully open the passage 98, the piston valve portion 102 closes the drain passage 100. The spacing of the piston valve portions 101 and 102 to control the passages in the manner stated also makes it possible to secure partial opening of the passage 98 and partial communication of the lower chamber 86 with the drain, with the result that the pressure supplied from the upper chamber 85 is reduced and only part correction in speed is obtained. Further 20 opening of the piston valve portion 101 will bring the pressure in the lower chamber 86 closer to that existing in the upper chamber 85 until the valve, at 98, is fully opened, in which position, the piston valve portion 102 of the valve closes 25 the drain and the pressure in the lower chamber will equal that in the upper chamber, thereby obtaining full isochronous operation.

The secondary or regulating pressure supplied to the passage 44, in accordance with any of the 30 modes of effecting governing operation, is furnished to the pressure chamber 41 of the relay device for securing operation of the pilot valve or servo-motor, the arrangement being such that the secondary or regulating pressure does not 35 move the pilot valve directly but merely changes the relationship of forces acting thereon so that differential forces are brought into play to bring about movement of the pilot valve, with the result that the servo-motor is quite sensitive to 40 small changes in secondary or regulating pressure. In other words, a change in secondary or regulating pressure applied to the abutment 49 brings about either upward or downward movement of the cup valve 50 and the pilot valve 53 45 moves in consequence of the change in pressure relation of the pressure in the chamber 51 and the pressure of the spring 78, with the result that the balanced relation of forces acting on the pilot valve is temporarily disturbed and the latter moves, movement of the pilot valve following that of the cup valve, movement downwardly being secured by the force of pressure in the chamber 51 preponderating over that of the spring 78 and upwardly due to preponderance of the spring 55 force over the fluid pressure force.

With movement of the cup valve 50 in consequence of change in secondary or regulating pressure due to load change of the turbine, the operating piston 66 is caused to move to change the 60 position of the admission valve, and, at the same time, the force of the spring 72 is being changed, this movement continuing until the force of the spring 72 and that of the secondary or regulating 65 pressure supplied to the cup valve are in equilibrium with the latter in position for neutral location of the pilot valve 53, at which time, the admission valve will be in suitable position for the changed load.

Standard, anticipating, and base load operations are similar in the respect that a percentage of regulation is required for operation of the apparatus from no load to full load, that is, at full load, the speed is slightly less than at no load, these operations being different in other respects, 75

the anticipating operation being used where large load changes are encountered to bring about over-travel of the spinner piston valve and consequent over-travel of the admission valve so as to anticipate the change in load in the direction of change. In the case of base load or sluggish operation, the only effect is to place the impedance of the accumulator 89 on the supply line 44 so as to suppress frequency fluctuations and prevent the latter from being impressed on the governor. In the case of isochronous operation, the turbine operates at the same speed at all loads, because the upper and lower piston areas 83 and 84 are equal, the force of the spring 26 is fixed, and the only other factor is the force of the primary pressure. Hence, to be in equilibrium, the primary pressure must be restored to its normal value corresponding to a constant speed. The only effect of the restriction in the passage 96 and the accumulator 99 is to introduce an impedance effect acting on the lower chamber 86 during the transient stage of going from one load to another, there being a temporary speed change followed by final adjustment of the apparatus to restore the speed of the turbine to its normal value at the new load. Isochronous operation is a special case of speed adjusting or correcting operation in which full speed correction or adjustment is made incident to load changes. As already pointed out, the valve means 98 may be manipulated so as to secure speed correction to any desired extent and to render speed correcting operation effective or ineffective. If such valve means is adjusted to interrupt the passage 96 and to afford communication of the lower pressure chamber 86 with the drain, then the speed correcting arrangement is ineffective, the governor being operable only for standard, anticipating, and base load conditions; and, if the valve means is adjusted so as to afford communication between the upper and lower pressure chambers, then the speed correcting arrangement is effective, the extent of speed correction being determined by adjustment of the valve means to vary the extent of communication of the lower chamber with the drain, restriction of the latter communication resulting in greater and greater speed correction until, with communication of the drain entirely interrupted, isochronous operation is secured. The valve means 98 makes it possible to change from an ordinary operating condition, such as standard operation, to isochronous operation without stopping the turbine. Assuming that the turbine is running under standard operation, then, to effect change therefrom to isochronous operation, it is merely necessary to adjust gradually the valve means, at 98, so that speed correction is gradually increased until full correction, corresponding to the isochronous condition, is secured. If it is desired to effect a speed change adjustment of the governing apparatus, this is done by adjusting the force of the spring 26 by any of the means illustrated.

While I have shown my invention in but one form, it will be obvious to those skilled in the art that it is not so limited but is susceptible of various changes and modifications without departing from the spirit thereof, and I desire, therefore, that only such limitations shall be placed thereupon as are specifically set forth in the appended claims.

What I claim is:

1. In a governor for prime movers of the type having an admission valve operated by pressure-

responsive means to control the supply of energy thereto, means for obtaining governing force varying as a function of the speed of the prime mover, a device for supplying fluid under regulating pressure to said pressure-responsive means and including means movable in response to change in governing force to change the regulating pressure in the same direction as the governing force, means for applying the regulating pressure to the movable means so as to balance the governing force, whereby a change in governing force due to a change in load and speed of the prime mover is followed by a change in regulating pressure in predetermined ratio thereto, and means for applying the regulating pressure gradually to said movable means so as to be effective in the same direction as the governing force, thereby temporarily changing the regulating pressure so as to operate the admission valve for speed correction of the prime mover allowing the gradually changing regulating pressure effective in the same direction as the governing force to replace the action of the latter on said means to secure pressure balance with the prime mover speed corrected and the governing pressure restored to its normal value.

2. In a governor for prime movers of the type having an admission valve operated by pressure-responsive means to control the supply of energy thereto, means for obtaining governing force varying as a function of the speed of the prime mover, a device for supplying fluid under regulating pressure to said pressure-responsive means and including means movable in response to change in governing force to change the regulating pressure in the same direction as the governing force, means for applying the regulating pressure to the movable means so as to balance the governing force, whereby a change in governing force due to a change in load and speed of the prime mover is followed by a change in regulating pressure in predetermined ratio thereto, means for applying regulating pressure gradually to the movable means in the same direction as the governing force, thereby temporarily changing the regulating pressure so as to operate the admission valve for speed correction of the prime mover and allowing the gradually changing regulating pressure acting in the same direction as the governing force to replace the action of the latter on said movable means to the extent of speed correction, and means for varying the ratio of the gradually applied pressure to the regulating pressure to vary the extent of speed correction.

3. In a governor for prime movers of the type having an admission valve operated by pressure-responsive means to control the supply of energy thereto, means for obtaining a governing force dependent upon prime mover speed; means for obtaining fluid under regulating pressure and for supplying the latter to the pressure-responsive means and including an aggregate which is movable to change the regulating pressure; means providing a biasing force acting on the aggregate; means for applying governing force to the aggregate in opposition to the biasing means; first means providing for the application of regulating pressure to the aggregate so that, when the governing force changes, the regulating pressure changes until the change in regulating pressure balances the change in governing force; and second means providing for the application of regulating pressure gradually to the aggregate and in the same direction as the

- governing force, thereby temporarily changing the regulating pressure so as to operate the admission valve for speed correction allowing the gradually changing regulating pressure acting 5 in the same direction as the governing force to replace the action of the latter in opposing said first means when the speed of the prime mover is corrected and said first and second means are in balance.
- 10 4. In a governor for prime movers of the type having an admission valve, means providing a first force varying as a function of the prime mover speed, a transformer providing a regulating fluid pressure, and a device responsive to regulating fluid pressure for controlling the admission valve; said transformer including an aggregate movable from a neutral position, in one direction, to increase the regulating fluid pressure, and, in the other direction, to decrease such pressure; means providing for application of said first force to the aggregate; biasing means applying a second force to the aggregate in opposition to the first force; means providing for application of a third force to the aggregate in a direction opposed to that of said first force and dependent upon the regulating fluid pressure; means responsive to change in regulating fluid pressure incident to change from one load condition to another to provide a fourth force opposing the third force; and means providing for adjustment of said fourth force so that it may be equal to or less than the third force for each load condition.
- 15 5. In a governing system for a prime mover having an admission valve and a pressure-responsive device for controlling the position of the admission valve, of provisions for supplying regulating pressure to the pressure-responsive device to effect adjustment of the admission valve 20 to meet a change in load with a small change in speed of the prime mover; said provisions comprising an element movable from neutral position, in one direction, to increase the regulating pressure, and in the other direction, to decrease the regulating pressure; means for developing a 25 governing force dependent upon prime mover speed and for applying said force to said element in the direction of movement thereof; means for applying a biasing force in opposed relation to the governing force; and means for applying to the element a third force dependent upon regulating pressure and in opposed relation to the governing force, whereby, with a change in load, the admission valve is adjusted until the change 30 in third force balances the change in governing force; and provisions for effecting further adjustment of the admission valve for speed adjustment of the prime mover and comprising means for applying to said element and in the same direction as the governing force a speed 35 adjusting fourth force dependent upon the regulating pressure; means for rendering the last-named means effective or ineffective and for securing any desired ratio of fourth force to third force over the range from zero to unity; and means for effecting gradual change in said fourth force relative to change in said third force to cause movement of said element and further change the regulating pressure to effect further adjustment of the admission valve until the prime mover speed is changed sufficiently to change the governing force an amount equal to the change in the fourth force.
- 40 6. The combination with a machine having a pressure-responsive controlling device, of means

providing a force dependent upon an operating characteristic of the machine, means providing a biasing force, means providing fluid under regulating pressure and for supplying the latter to said pressure-responsive controlling device, the last-named means including an element acted on by said forces and movable in response to change of the first force to change the regulating pressure, first means including a piston area for applying regulating pressure to said element so that changes in such pressure are applied concurrently as they occur, second means including a piston area for applying regulating pressure to said element in opposed relation to said first means, and means cooperating with said second means to secure delayed application thereby to said element of changes in regulating pressure.

7. In a governor for prime movers of the type having an admission valve, a pressure-responsive device for operating the admission valve, means providing a governing force dependent upon prime mover speed, means providing a biasing force, means providing fluid under regulating pressure and for supplying the latter to said pressure-responsive device, the last-named means including a piston valve acted on by said forces and movable in consequence of change of governing force to change the regulating pressure, said piston valve having first and second piston areas with the first area facing in the direction of the governing force, means for applying fluid under regulating pressure to the first and second piston areas, and means cooperating with the last-named means to provide for delayed application of changes in regulating pressure to the second piston area.

8. In a governor for prime movers of the type having an admission valve, means providing a governing force dependent upon an operating condition of the prime mover, a transformer providing a regulating fluid pressure, and a device responsive to regulating fluid pressure for controlling the admission valve; said transformer including an element movable from a neutral position, in one direction, to increase the fluid pressure, and, in the other direction, to decrease such pressure; means providing for the application of said governing force to the element in the path of movement thereof; biasing means exerting its effect on the movable element in opposition to the governing force; opposed and equal first and second piston areas for the movable element; said first piston area facing in such a direction that pressure applied thereto exerts a force on the movable element in the same direction as the biasing means; means for applying regulating fluid pressure to the first piston area; and means responsive to change in regulating fluid pressure incident to change in load to provide for the application to the second piston area of fluid under pressure which is equal to or less than the regulating pressure.

9. The combination with a machine having a fluid pressure responsive controlling device, of means providing a force dependent upon speed of the machine; means for transforming said force into fluid under regulating pressure and including a movable aggregate; said aggregate comprising a movable abutment subject to said force, biasing means acting on the abutment in opposition to said force, and a piston valve abutting said abutment; means for imparting spinning motion to the piston valve; means including a first piston area for applying to the piston valve,

and in opposition to said force, changes in regulating pressure concurrently as they occur; means including a second piston area for gradually applying to the piston valve, and in the same direction as said force, changes in said regulating pressure; and means for supplying fluid under regulating pressure to said device.

10. In a governor for prime movers of the type having an admission valve, means providing a governing pressure varying as an operating characteristic of the prime mover, a transformer providing a regulating fluid pressure; a device responsive to regulating fluid pressure for controlling the admission valve; said transformer including an element movable from a neutral position, in one direction, to increase the regulating pressure, and, in the other direction, to decrease such pressure; first, second and third abutment areas for the movable element; the second and third areas being equal and facing in opposite directions with the first area facing in the same direction as the third area; means for applying fluid under governing pressure to the first area; biasing means exerting its effect 25 on the movable element in opposition to the governing pressure; means providing first and second pressure chambers for the second and third areas, respectively; means for supplying fluid under regulating pressure to the first chamber; means providing a passage connecting the first and second chambers, orifice means for said passage; and an accumulator communicating with said passage between the orifice means and the second chamber.

35. 11. In a governor for prime movers of the type having an admission valve, means providing a governing pressure varying as an operating characteristic of the prime mover, a transformer providing a regulating fluid pressure; a device responsive to regulating fluid pressure for controlling the admission valve; said transformer including an element movable from a neutral position, in one direction, to increase the regulating pressure, and, in the other direction, to decrease such pressure; first, second and third abutment areas for the movable element; the first and second areas facing in opposite directions and the second area facing in the same direction as the third area; means for applying 50 fluid under governing pressure to the third area; biasing means exerting its effect on the movable element in opposition to the governing pressure; means providing first and second pressure chambers for the first and second areas; means for supplying fluid under regulating pressure to the first chamber; passages for connecting the first and second chambers and for draining the second chamber; orifice means for the passage connecting the chambers; an accumulator communicating with the connecting passage between the orifice means and the second chamber; and valve means providing for opening and closing of said passages.

65. 12. The combination with a machine having a control element, of governing mechanism including means providing a governing force: means operated in response to fluid pressure to position said control element and including a supply passage: means providing pressure supply 70 and exhaust connections: means for transforming governing force changes into pressure changes and comprising a pressure control valve aggregate including a control valve movable in opposite directions to provide, in cooperation with said connections, a source of fluid under

transformed pressure for said supply passage: means for biasing the aggregate to move the control valve in one direction: means for applying said governing force to the aggregate to effect movement of the control valve in the other direction: means providing a pressure chamber closed by a movable pressure abutment operatively connected to the control valve and disposed so that pressure applied thereto provides a force opposing said governing force: accumulator means: passages for connecting said supply source to said pressure chamber and to said supply passage and for connecting the accumulator means to said pressure chamber and to the supply passage: and means including manipulatable valves cooperating with said passages, for standard operation, to isolate the accumulator means and to provide for unrestricted communication of said supply source with the pressure chamber and with the supply passage; and, for anticipating operation, to provide for restricted orifice communication of said source with the pressure chamber and for unrestricted communication of said source with the supply passage and of the accumulator means with the pressure chamber.

13. The combination with a machine having a control element, of governing mechanism including means providing a governing force: means operated in response to fluid pressure to 30 position said control element and including a supply passage: means providing pressure supply and exhaust connections: means for transforming governing force changes into pressure changes and comprising a pressure control valve 35 aggregate including a control valve movable in opposite directions to provide, in cooperation with said connections, a source of fluid under transformed pressure for said supply passage: means for biasing the aggregate to move the 40 control valve in one direction: means for applying said governing force to the aggregate to effect movement of the control valve in the other direction: means providing a pressure chamber closed by a movable pressure abutment operatively connected to the control valve and disposed so that pressure applied thereto provides a force opposing said governing force: accumulator means: passages for connecting said supply 45 source to said pressure chamber and to said supply passage and for connecting the accumulator means to said pressure chamber and to the supply passage: and means including manipulatable valves cooperating with said passages, for standard operation, to isolate the accumulator 50 means and to provide for unrestricted communication of said supply source with the pressure chamber and with the supply passage; and, for base load operation, to provide an orifice in the supply passage restricting flow therealong from 55 the source, for unrestricted communication of said source with the pressure chamber, and for communication of the accumulator means with said supply passage at the side of the orifice remote from said source.

65. 14. The combination with a machine having a control element, of governing mechanism including means providing a governing force: means operated in response to fluid pressure to position said control element and including a 70 supply passage: means providing pressure supply and exhaust connections: means for transforming governing force changes into pressure changes and including a pressure control valve movable in opposite directions to provide, in co- 75

- operation with said connections, a source of fluid under transformed pressure for said supply passage: means for moving said control valve including means providing for application of governing force thereto and means providing a pressure chamber closed by a movable pressure abutment operatively connected to the control valve and disposed so that pressure applied thereto provides a force opposing said governing force: accumulator means: passages for connecting said supply source to said pressure chamber and to said supply passage and for connecting the accumulator means to said pressure chamber and to the supply passage: and means including manipulatable valves cooperating with said passages, for standard operation, to isolate the accumulator means and to provide for unrestricted communication of said supply source with the pressure chamber and with the supply passage; for anticipating operation, to provide for restricted orifice communication of said source with the pressure chamber and for unrestricted communication of said source with the supply passage and of the accumulator means with the pressure chamber; and, for base load operation, to provide an orifice in the supply passage restricting flow therealong from the source, for unrestricted communication of said source with the pressure chamber, and for communication of the accumulator means with said supply passage at the side of the orifice remote from said source.

15. The combination with a machine having a control element, of governing mechanism including means providing a governing force: means operated in response to fluid pressure to position said control element and including a supply passage: means providing pressure supply and exhaust connections: means for transforming governing force changes into pressure changes and including a pressure control valve movable in opposite directions to provide, in cooperation with said connections, a source of fluid under transformed pressure for said supply passage: means for moving said control valve including means providing for application of governing force thereto and means providing first and second pressure chambers closed by first and second movable pressure abutments operatively connected to the control valve, said pressure abutments being arranged in opposed relation and the first abutment being so disposed that pressure applied thereto provides a force acting on the control valve which opposes the governing force: accumulator means: passages affording communication of said source with said first and second chambers and with the supply passage, connecting the accumulator means to said first and second chambers and to the supply passage and providing for drainage from the second chamber: means including manipulatable valves cooperating with said passages, for standard operation, to provide an orifice restricting flow from the source and along the supply passage, to provide unrestricted communication of said source with the first pressure chamber, to provide for communication of the accumulator means with said supply passage at the side of the orifice remote from said source, and to drain said second pressure chamber; and, for speed-adjusting operation, to provide for unrestricted communication of the source with the first chamber and with the supply passage, for an orifice between the source and the second pressure chamber, for communication of the accumulator means with the second pressure chamber, and for drainage adjustment of the second chamber to vary the pressure attainable therein as required by the extent of speed adjustment.

16. The combination with a machine having a control element, of governing mechanism including means providing a governing force: means operated in response to fluid pressure to position said control element and including a supply passage: means providing pressure supply and exhaust connections: means for transforming governing force changes into pressure changes and including a pressure control valve movable in opposite directions to provide, in cooperation with said connections, a source of fluid under transformed pressure for said supply passage: means for moving said control valve including means providing for application of governing force thereto and means providing first and second pressure chambers closed by first and second movable pressure abutments operatively connected to the control valve, said pressure abutments being arranged in opposed relation and the first abutment being so disposed that pressure applied thereto provides a force acting on the control valve which opposes the governing force: accumulator means: passages affording communication of said source with said first and second chambers and with the supply passage, connecting the accumulator means to said first and second chambers and to the supply passage and providing for drainage from the second chamber: means including manipulatable valves cooperating with said passages, for standard operation, to provide an orifice restricting flow from the source and along the supply passage, to provide unrestricted communication of said source with the first pressure chamber, to provide for communication of the accumulator means with said supply passage at the side of the orifice remote from said source, and to drain said second pressure chamber; and, for speed-adjusting operation, to provide for unrestricted communication of the source with the first chamber and with the supply passage, for an orifice between the source and the second pressure chamber, for communication of the accumulator means with the second pressure chamber, and for drainage adjustment of the second chamber to vary the pressure attainable therein as required by the extent of speed adjustment.

17. The combination with a machine having a control element, of governing mechanism including means providing a governing force: means operated in response to fluid pressure to position said control element and including a supply passage: means providing pressure supply and exhaust connections: means for transforming governing force changes into pressure changes and including a pressure control valve movable in opposite directions to provide, in cooperation with said connections, a source of fluid under transformed pressure for said supply passage: means for moving said control valve including means providing for application of governing force thereto and means providing first and second pressure chambers closed by first and second movable pressure abutments operatively connected to the control valve, said pressure abutments being arranged in opposed relation and the first abutment being so disposed that pressure applied thereto provides a force acting on the control valve which opposes the governing force: accumulator means: passages affording communication of said source with said first and second chambers and with the supply passage, connecting the accumulator means to said first and second chambers and to the supply passage and providing for drainage from the second chamber: means including manipulatable valves cooperating with said passages, for standard operation, to provide an orifice restricting flow from the source and along the supply passage, to provide unrestricted communication of said source with the first pressure chamber, to provide for communication of the accumulator means with said supply passage at the side of the orifice remote from said source, and to drain said second pressure chamber; and, for speed-adjusting operation, to provide for unrestricted communication of the source with the first chamber and with the supply passage, for an orifice between the source and the second pressure chamber, for communication of the accumulator means with the second pressure chamber, and for drainage adjustment of the second chamber to vary the pressure attainable therein as required by the extent of speed adjustment.

sage: means for moving said control valve including means providing for application of governing force thereto and means providing first and second pressure chambers closed by first and second movable pressure abutments operatively connected to the control valve, said pressure abutments being arranged in opposed relation and the first abutment being so disposed that pressure applied thereto provides a force 5 acting on the control valve which opposes the governing force: accumulator means: passages affording communication of said source with said first and second chambers and with the supply passage, connecting the accumulator means to said first and second chambers and to the supply passage and providing for drainage from the second chamber: means including manipulatable valves cooperating with said passages, for anticipating operation, to provide for unrestricted 10 orifice communication of said source with the first pressure chamber, to provide for unrestricted communication of said source with the supply passage and of the accumulator means with the pressure chamber, and to provide drainage for the second pressure chamber; and, for speed-adjusting operation, to provide for unrestricted communication of the source with the first chamber and with the supply passage, for an orifice between the source and the second 15 pressure chamber, for communication of the accumulator means with the second pressure chamber, and for drainage adjustment of the second chamber to vary the pressure attainable therein as required by the extent of speed adjustment. 20

18. The combination with a machine having a control element, of governing mechanism including means providing a governing force: means operated in response to fluid pressure to position 25 said control element and including a supply passage: means providing pressure supply and exhaust connections: means for transforming governing force changes into pressure changes and including a pressure control valve movable in opposite directions to provide, in cooperation with said connections, a source of fluid under transformed pressure for said supply passage: means for moving said control valve including means providing for application of governing 30 force thereto and means providing first and second pressure chambers closed by first and second movable pressure abutments operatively connected to the control valve, said pressure abutments being arranged in opposed relation and the first abutment being so disposed that pressure applied thereto provides a force 35 acting on the control valve in opposition to the resultant of the governing and spring force: accumulator means: passages affording communication of said source with said first and second chambers and with the supply passage, connecting the accumulator means to said first and second chambers and to the supply passage, and providing for drainage from the second pressure chamber: and means including manipulatable valves cooperating with said passages, for standard operation, to provide for isolation of the accumulator means, to drain the second pressure chamber, and to provide for unrestricted 40 communication of said source with the first chamber and with the supply passage; and, for speed-adjusting operation, to provide for unrestricted communication of said source with the first pressure chamber and with the supply passage, to provide an orifice restricting flow from said source to the second pressure chamber, to provide for communication of the accumulator means with the second pressure chamber, and to provide for drainage adjustment of the second chamber to vary the pressure of latter as required 45 by the extent of speed adjustment. 50

20. The combination with a machine having a control element, of governing mechanism including means providing a governing force: means operated in response to fluid pressure to position 55 said control element and including a supply passage: means providing pressure supply and exhaust connections: means for transforming governing force changes into pressure changes which are larger than but proportionate to the force changes and including a pressure control valve movable in opposite directions to provide, in cooperation with said connections, a source of fluid under transformed pressure for said supply passage: means for moving said control valve including means providing for application of governing force thereto and means providing first and second pressure chambers closed by first and second pressure abutments operatively connected 60 to the control valve, said pressure abutments being arranged in opposed relation and the first pressure abutment being so disposed that pressure applied thereto provides a force acting on the control valve in opposition to the resultant of the governing and spring forces: first and second accumulators: passages affording communication of said source with said first and second chambers and with the supply passage, connecting the first accumulator to the first 65 chamber or to the supply passage, connecting the 70

75 19. The combination with a machine having

- second accumulator to the second pressure chamber, and for draining the second pressure chamber: manipulatable valve means cooperating with said passages, for standard operation, to 5
5 isolate the first and second accumulators, to drain the second pressure chamber, and to provide for unrestricted communication of the supply source with the first pressure chamber and with the supply passage; for anticipating operation, to 10
10 provide for restricted orifice communication of the source with the first pressure chamber, for unrestricted communication of the source with the supply passage and of the first accumulator with the first pressure chamber, for isolation 15
15 of the second accumulator and for drainage of the second pressure chamber; for base load operation, to provide an orifice restricting flow from said source and along the supply passage, to provide unrestricted communication of the source 20
20 with the first pressure chamber, to provide for communication of the first accumulator with the supply passage at the side of the orifice remote from the source, and to provide for drainage of the second pressure chamber; and, for speed- 25
25 adjusting operation, to provide for unrestricted communication of the source with the first pressure chamber and with the supply passage, for an orifice restricting flow from the source to the second pressure chamber, and for adjustment of drainage from the second chamber as determined 30
30 by the desired speed adjustment.

21. In a governor for prime movers of the type having an admission valve, means providing a governing force varying as a function of the speed of the prime mover, a transformer responsive to changes in governing force to provide changes in regulating fluid pressure, a device responsive to said regulating fluid pressure for con-

trolling the admission valve, means responsive to speed change incident to load change for modifying the action of said transformer to control the regulating fluid pressure provided thereby so that in changing from one load condition to another the prime mover speed at the new load condition is restored to the value it had at the old load condition, and means for rendering the last-named means effective or ineffective. 5

22. The combination with a prime mover having a valve, of governing mechanism providing a regulating pressure varying as an operating characteristic of the prime mover, a servo-motor including an operating element connected to said valve and a pilot valve for controlling the admission and exhaust of motive fluid to the operating element, means providing a pressure chamber into which one end of the pilot valve extends, means including an orifice for supplying fluid under pressure to the pressure chamber, means 10 controlling the escape of fluid from the pressure chamber including a bore formed in the pilot valve and an escape-controlling valve cooperating therewith, a first spring for biasing the pilot valve toward the escape-controlling valve, means 15 for positioning the pilot valve including a second spring and an abutment subject to fluid under regulating pressure, and means responsive to movement of the operating element to change the force of the second spring so as to restore equilibrium of forces acting on the pilot valve with the latter in position for restoration of the pilot valve to neutral position by the force of the first spring and of the pressure in said pressure chamber and acting on the end of the pilot valve 20 25 30 35 therein. 25
